Specification for Design.

Patented July 23, 1912.

Application filed May 9, 1912. Serial No. 696,243. Term of patent 14 years.

To all whom it may concern:

Be it known that I, EDWIN P. WANNER, a citizen of the United States, residing at New York city, in the county of New York and State of New York, have invented a certain new, original, and ornamental Design for a Combined Leg-Brace and Foot-Ring Rest for Stools, of which the following is a specification.

The drawing shows the combined leg brace and foot ring rest for stools and the like in plan, Figure 1, and in side elevation, Fig. 2.

The strap or band α is quadrilateral in

plan and approximates the shape of a square. Rising from each of the corners b of the strap are the outwardly bent uprights or supports c .

I claim:

The ornamental design for a combined leg-brace and foot-ring rest for stools substantially as shown and described.

In testimony whereof I affix my signature in presence of two witnesses.

EDWIN P. WANNER.
